(57) **CLAIM**

The ornamental design for electronic circuit device, as shown and described.

DESCRIPTION

FIG. 1 is a top-front-left perspective view of the electronic circuit device of my new design;

FIG. 2 is a front view thereof;

FIG. 3 is a right side view thereof;

FIG. 4 is a top view thereof;

FIG. 5 is a left side view thereof;

FIG. 6 is a bottom view thereof; and,

FIG. 7 is a rear view thereof.

The broken lines depict portions of the electronic circuit device that form no part of the claim.
